UNITED STATES PATENT OFFICE.

WILLIAM H. CREIGHTON, OF NEW EAGLE, PENNSYLVANIA.

SAFETY-VALVE.

No. 850,626.

Specification of Letters Patent.

Patented April 16, 1907.

Application filed August 8, 1906. Serial No. 329,779.

To all whom it may concern:

Be it known that I, WILLIAM H. CREIGHTON, a citizen of the United States of America, residing at New Eagle, in the county of Washington and State of Pennsylvania, have invented certain new and useful Improvements in Safety-Valves, of which the following is a specification, reference being had therein to the accompanying drawings.

This invention relates to certain new and useful improvements in safety-valves, particularly designed for gas-supply pipes.

My invention has for its object the provision of novel means for automatically closing a gas-supply pipe should the pressure of gas be diminished or entirely shut off. To this end I have devised a safety-valve adapted to prevent persons from being asphyxiated in a compartment where gas is used as a fuel or for illuminating purposes. In this connection my improved valve is located at a convenient place upon the gas-supply pipe, whereby it can be easily reached and opened should the same be closed by a reduction in the pressure of gas. It is a well-known fact that persons have been asphyxiated while sleeping by the supply of gas being cut off and then turned on again and escaping through the burner without being ignited. My invention aims to obviate this danger by the provision of novel means for automatically closing the gas-supply pipe when the gas-supply is shut off.

The detail construction of my improved safety-valve will be hereinafter more fully described, illustrated, and the main features thereof specifically pointed out in the appended claims.

Referring to the drawings forming part of this specification, like numerals of reference designate corresponding parts throughout the several views, in which—

Figure 1 is a vertical sectional view of my improved valve, illustrating the valve in a closed position. Fig. 2 is a transverse sectional view thereof. Fig. 3 is a similar view, illustrating the valve in an open position; and Fig. 4 is a perspective view of a pivoted locking-disk used in connection with the same.

My improved safety-valve consists of a cylindrical body portion 1, the lower end of the bore 2 thereof being threaded, as at 3, to receive the threaded end of a gas-supply pipe 4. The valve-body 1 is formed with an angular projection 5, having a screw-threaded re-

cess 6 formed therein to receive the end of an inlet-pipe (not shown) that communicates with a suitable burner, either for heating or illuminating purposes. The recess 6 communicates with the bore 2 of the valve-body by an outlet-port 7.

The upper end of the valve-body 1 is closed except for a central opening 8, and extending upwardly from the top of the valve-body are two diametrically-opposed arms 9, the upper ends of which are provided with openings 10. In the bore 2 of the valve-body 1 is mounted a valve-head 11, having a vertically-disposed stem 12, which extends upwardly through the opening 8 of the valve-body. To cushion the valve-head 11 within the valve-body, resilient washers or gaskets 14 are placed in each end of the bore 2 thereof.

Pivotedly mounted between the arms 9 is a locking-disk 15, said disk being retained between said arms by a pin 16, mounted in the openings 10 of the arms 9. The locking-disk is provided with a tooth 17, adapted to limit the movement of said disk, and with a conventional form of handle 18, whereby the disk can be easily manipulated.

The normal position of my improved valve is illustrated in Fig. 3 of the drawings, where it will be observed that the valve-head 11 is in an elevated position, permitting gas to pass from the pipe 4 through port 7 into the recess 6 and the connecting-pipe thereof. The pressure of gas entering the valve-body 1 is adapted to maintain the valve-head 11 in the elevated position shown in Fig. 3, and the stem which normally engages the disk 15 retains said disk in a partially-elevated position. Should the supply of gas be shut off, the weight of the valve-head 11 and the disk 15 causes the valve-head 11 to descend by gravity until it seats upon the lowermost washer or gasket 14. The valve-head not only closes the pipe 4, but closes the port 7, and is prevented from rising by the disk 15 being interposed between the upper end of the stem 12 and the disk's pivotal connection with the arms 9. The tooth 17 of the disk 15 is adapted to impinge against the side of the stem 12, at the upper end thereof, and correctly position the disk 15, whereby one of its diameters will lie in alinement with the pivotal connection of said disk and the upper end of the stem 12.

Should the gas-supply be turned on, it will be impossible for the gas to escape until the disk 15 is elevated to the position shown in Fig. 3 of the drawings. It

is obvious that the inlet and outlet of my improved valve can be reversed, the pipe 4 serving as an outlet-pipe, while the port 7 serves as an inlet-port.

5 It is thought from the foregoing description, taken in connection with the drawings, that the operation of my improved safety-valve will be readily apparent, especially to those skilled in this art. I do not care to 10 confine myself to the size, proportion, or material used in connection with my improved valve, and I wish it to be understood that such changes in the details of construction as are permissible by the appended claims 15 may be resorted to without departing from the spirit and scope of the invention.

What I claim, and desire to secure by Letters Patent, is—

1. In a safety-valve, the combination 20 with a suitable gas-supply pipe, of a valve-body connected to said supply-pipe and having an outlet-port formed therein, upwardly-extending arms carried by said valve-body, a valve-head slidably mounted in said valve-

body, a stem carried by said head and extending upwardly through said valve-body between said arms, a locking-disk pivotally mounted between said arms and engaging said stem, a tooth carried by said disk and adapted to limit the movement thereof, substantially as described.

2. In a safety-valve, a valve-body having an outlet-port, upwardly-extending arms carried by said valve-body, a valve-head 35 slidably mounted in said valve-body, a stem carried by said head and extending upwardly through said body between said arms, a locking-disk pivotally mounted between said arms and engaging said stem, and a tooth on said disk adapted to impinge against the stem and limit the rotative movement of the disk in one direction.

In testimony whereof I affix my signature in the presence of two witnesses.

WILLIAM H. CREIGHTON.
